US00D331247S

United States Patent [19]

Okuda

[11] Patent Number: Des. 331,247

[45] Date of Patent: ** Nov. 24, 1992

[54] **NUMERICALLY CONTROLLED DRILLING MACHINE**

4,601,094 7/1986 Myers 483/3
4,742,609 5/1988 Neumann 483/3
4,831,714 5/1989 Badel et al. 483/3

[75] Inventor: Shinji Okuda, Oshino, Japan

Primary Examiner—Donal P. Walsh

[73] Assignee: Fanuc Ltd., Minamitsuru, Japan

Assistant Examiner—Antonio D. Davis

[**] Term: 14 Years

Attorney, Agent, or Firm—Staas & Halsey

[21] Appl. No.: 661,088

[57] CLAIM

[22] Filed: Feb. 26, 1991

The ornamental design for a numerically controlled drilling machine, as shown.

[30] Foreign Application Priority Data

Oct. 5, 1990 [JP] Japan 2-23425

DESCRIPTION

[52] U.S. Cl. D15/132

FIG. 1 is a front elevational view of a numerically controlled drilling machine showing my new design;

[58] Field of Search D15/132, 199; 29/568;
483/3

FIG. 2 is a right side elevational view;
